(57) **CLAIM**

The ornamental design for door edge plate, as shown and described.

DESCRIPTION

FIG. 1 is a front perspective view of door edge plate showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom view thereof; and,

FIG. 7 is a top view thereof.

The broken lines shown in the drawings represent portions of the door edge plate that form no part of the claimed design.
